CLOSURE FASTENER

William H. Wrye, Philadelphia, Pa.

Application November 9, 1931, Serial No. 574,002

7 Claims. (Cl. 229—84)

This invention relates to an improved closure fastener means having its widest field of use in connection with paper receptacles, particularly those of the envelope type.

5 An object of the invention is the provision of a novel closure fastener means including a locking tongue having relatively movable portions adapted to be placed in registry for interlocking engagement with a keeper.

10 Another object is the provision in a closure fastener of a novel locking tongue including overlapping offset sections adapted to be moved into registry for locking engagement with a keeper.

A further object is the provision in a closure fastener of a co-acting arrangement of keeper and locking tongue whereby the tongue is caused automatically to function through its engagement with the keeper. Other objects include novel keeper means and arrangements for mounting the same on receptacles to which the invention is applied.

The present disclosure illustrates certain physical embodiments of the principles of this invention and constitutes the best means thus far devised for reducing the invention to practice. It is understood that the structural details of the disclosure shall not constitute limitations inconsistent with the scope of the invention as claimed.

In the drawings:

30 Figure 1 is a perspective of an envelope having a closure fastener thereon as constructed in accordance with the invention and illustrating the fastener as in locked position.

Figure 2 is an enlarged face view of a fastener as shown in Figure 1.

35 Figure 3 is a face view of the fastener means of Figures 1 and 2, but illustrating the locking tongue as flexed in the act of engagement with a keeper prior to interlocking therewith.

40 Figure 4 is a section on the line 4—4 of Figure 3.

Figure 5 is a section on the line 5—5 of Figure 2.

45 Figure 6 is a perspective of the locking tongue employed as an element of the fastener.

Figure 7 is a plan view of the blank from which the locking tongue is constructed.

50 Figure 8 is a perspective of the keeper means as shown in Figures 1 to 4.

Figure 9 is a face view of the rear of an envelope equipped with an alternative form of closure fastener.

55 Figure 10 is a section on the line 10—10 of Figure 9.

Figure 11 is a face view of the wall portion of

an envelope having an alternative form of keeper means secured thereon.

Figure 12 is a section on the line 12—12 of Figure 11.

Figure 13 is a face view of an envelope wall having a further alternative structural arrangement of keeper means associated therewith. 60

Figure 14 is a section on the line 14—14 of Figure 13.

Figure 15 is a face view of an envelope wall 65 having a still further embodiment of keeper means associated therewith.

Figure 16 is a section on the line 16—16 of Figure 15.

Figure 17 is a perspective of the keeper means 70 illustrated in Figure 15.

Figure 18 is a face view of an envelope wall having another structural embodiment of keeper means associated therewith.

Figure 19 is a section on the line 19—19 of Figure 18.

Figure 20 is a rear face view of an envelope and closure flap having a further alternative embodiment of closure fastener wherein the action of the locking tongue is automatic with respect to 80 the keeper means.

Figure 21 is a section on line 21—21 of Figure 20.

Figure 22 is a perspective of one of the keeper elements as used in the construction illustrated 85 in Figure 20.

In the present disclosure my improved closure fastener means is illustrated as employed in connection with paper or cardboard receptacles of the envelope type which generally, as shown in Figure 1, include a back wall portion 25 and a closure flap portion 26 foldable downwardly thereover from the upper edge of the front wall in the conventional manner. In all embodiments of the invention the fastener means includes a 90 keeper arranged on the rear wall of the envelope and a locking tongue carried by the closure flap and adapted to interlock with the keeper by insertion into engagement therewith.

As illustrated in Figures 1 to 8 inclusive the 100 rear wall 25 of the receptacle has appropriately secured to the external face thereof a keeper comprising in this instance a rectangular strip 27 of relatively stiff paper or cardboard, the length of which is greater than its width. At each side edge of the body strip of the keeper integral lateral ears 28 are provided, which ears are adapted to be passed through slits formed for the purpose in the rear wall 25 of the envelope. Engagement through the slits in the envelope wall 110

portion effectively secures the keeper strip in position and a light application of some suitable cementing material or glue may be employed to hold the parts in place. At suitably spaced intervals the body of the keeper is provided with transversely disposed slots 29 adapted to receive therethrough the locking tongue means about to be described.

The locking tongue is preferably formed by cutting from a blank of material of some measure of flexibility coupled with a slight inherent resiliency. One such material is heavy paper or cardboard stock. As shown in Figure 7 a blank is cut to provide a substantially rectangular central portion 30 from which extend oppositely directed tongues 31 and 32 arranged in offset relation with respect to the longitudinal meridian of the blank having at their outer ends hooks 33 and 34 which are oppositely directed with respect to each other. The outer terminal faces of the hooked heads 33 and 34 are provided with the respective rounded edges 35 and 36 and between the heads and the central portion 30 the opposite side edges of each tongue section 31 and 32 are arranged as inclined edges converging toward the heads. In forming the tongue the blank is bent upon itself at its central portion along the line of fold, as shown by the dotted line in Figure 7. The offset arrangement of the tongue sections 31 and 32 disposes these elements normally disaligned with respect to each other and one of the sections such as 31 is slightly greater in length than the other so that when the sections are folded into overlapping relationship the heads 33 and 34 are arranged in staggered relation, as best illustrated in Figure 6.

The tongue is secured to the receptacle closure flap portion by passing the overlapped tongue sections through a slot provided for the purpose in the closure flap in such manner that the folded central portion 30 of the tongue is disposed against the inner face of the closure flap to which it may be secured by cement or glue. The width of the closure flap slot through which the overlapped tongue sections are passed is no greater than the width of the tongue sections at their bases and accordingly the width of the slot is not as great as the width of the folded central portion 30 of the tongue element. This arrangement serves to anchor the tongue with respect to the closure flap.

As shown in Figures 3 and 4 the locking function of the closure fastener is accomplished by flexing the overlapping tongue sections 31 and 32 into an arched position as shown best in Figure 4, while at the same time the tongue sections are moved laterally under manual compression to bring the heads 33 and 34 into registry so that they may be inserted within the selected one of the keeper slots 29. The rounded entrant edges of the tongue section heads permit a ready entry of the tongues through the selected slot beneath the body of the keeper and as the length of the slots 29 is only slightly greater than the width of the tongue section heads when in registry, it will be apparent that when the heads of the locking tongue sections have passed through the keeper slot the heads will move laterally in opposite directions upon a release of the manual compression under the inherent resilient of the material from which the tongue is formed whereby to dispose the respective heads 33 and 34 into interlocking engagement with the keeper as shown in Figure 2. When a release of the locking engagement is desired it is merely necessary to move

the tongue sections inwardly with respect to each other under manual compression to bring the heads again into registry whereupon they may be removed from engagement with the keeper.

In the structural embodiment of closure fastener shown in Figures 9 and 10 structural details of the locking tongue are the same as those previously described except that the length of the two tongue sections is equal. Accordingly, the same reference characters are given to these parts in Figures 9 and 10. A structural difference resides in the particular arrangement of the keeper which in this form consists merely of a single rectangular strip 37 anchored to the rear wall of the receptacle 25 by passing the ends of the strip inwardly through spaced parallel slots provided for the purpose in the receptacle wall. The width of the keeper thus formed on the back of the receptacle coincides with the distance between the parallel slots in the rear wall, which distance is less than the width of the tongue heads when in normal disaligned position. The effective width of the keeper corresponds substantially to the width of one head of the locking tongue sections. The manner of applying and releasing the fastener is the same as that described in connection with the form shown in Figures 1 to 8 inclusive.

In Figures 11 and 12 there is illustrated an alternative arrangement of keeper wherein an elongated keeper strip 38 is disposed on the inner face of the receptacle wall portion 25 and is provided with tabs 39 at its opposite ends, which tabs extend through slots provided for the purpose in the wall. The keeper strip is provided with parallel spaced tongue receiving slots 40 which register with similar slots 41 provided in the wall portions. This form of keeper is designed to accommodate the fastener to receptacles wherein expansion is desired.

In the embodiment illustrated in Figures 13 and 14 an elongated rectangular keeper strip 42 has its major portion disposed on the outer face of the receptacle wall portion 25 and has its opposite end portions passed inwardly through slots provided for the purpose in the wall portion. The keeper is provided with spaced tongue receiving slots 43 and is further provided at its opposite side edges with lateral tabs 44 in line with each of the slots 43 and passed through slots provided for the purpose in the wall portion 25.

In the embodiment shown in Figures 15, 16 and 17 an elongated rectangular keeper strip 45 is passed beneath webs 46 which are formed on the envelope wall portion 25 by appropriately placed slots through which the keeper strip is threaded to dispose the major portion thereof on the outer face of the wall. At one end the keeper strip is provided with a laterally enlarged head 47 which limits the inserting movement of the keeper strip and the body of the strip is additionally provided with a plurality of spaced tongue receiving slots 48.

The keeper strip embodiment illustrated in Figures 18 and 19 is an elaboration of the form shown in Figures 13 and 14. In this further embodiment the keeper strip is formed as a relatively long and narrow band 49 provided with longitudinally spaced tabs 50 extending from the opposite side edges and passed through securing slots provided for the purpose in the wall portion 25. At each end of the band 49 the terminal portions are passed inwardly through securing slots provided therefor in the receptacle wall.

As in the other forms the body of the keeper is provided with a plurality of spaced parallel tongue receiving slots 51.

The closure fastener means illustrated in Figures 20, 21 and 22 employs a tongue construction identical with that illustrated in Figures 1 to 7 inclusive and like reference characters have been given to like parts. However, in this embodiment the keeper consists of a plurality of spaced parallel bands 52 arranged with their end terminal portions 53 passed through diagonally converging slots provided for the purpose in the rear wall 25 of the receptacle. The central portions of the bands 52 are bulged outwardly to provide raised keeper bars 54 formed with end walls disposed in the planes of the slots through which the ends 53 of the bands are passed. This construction provides at each keeper band a socket provided with wall portions which converge in the entrant direction of the tongue means. The greatest width of the socket walls substantially equals the width of the tongue section heads when in normal offset position and the minimum width of the socket walls equals substantially the width of one head so that as the tongue sections are pushed beneath the keeper bands the converging walls of the sockets will move the overlapping heads automatically into registry to permit passage of the tongue. In disengaging the tongue the uppermost tongue section is moved laterally to register its head with the socket whereupon it may be withdrawn. The lowermost tongue section is then moved in like manner and withdrawn.

In each instance of the keeper strips and bands it is to be understood that in addition to the securing action of the tabs and ears which pass through the slots in the receptacle walls, a suitable adhesive is applied to all engaging areas of the keeper strips and receptacle wall. The keeper strips and bands are formed of suitably heavy or semi-rigid material so that an effective reinforcement is provided for the receptacle wall

over all that portion occupied by the keeper. In this manner tearing strain of the tongue sections is eliminated.

I claim:

1. Closure fastener means comprising a keeper, and a tongue consisting of offset normally overlapped sections mutually slidably into superimposed registry for locking engagement therewith. 80
2. In a closure fastener a locking tongue comprising a one-piece strip of material doubled upon itself to provide normally overlapping sections offset with respect to each other. 85
3. In a closure fastener a tongue comprising a strip of flexible material doubled upon itself to form offset normally overlapped sections and oppositely directed locking heads on the ends of said sections. 90
4. Closure fastener means comprising a keeper, a locking tongue, normally overlapped heads on said tongue and normally offset with respect to each other, and said heads being mutually movable into registry to engage said keeper. 95
5. In a closure fastener, a keeper, and a locking tongue engageable therewith, said tongue having normally overlapped superimposed resilient sections normally offset with respect to each other and compressible into registry to engage the keeper. 100
6. In a closure fastener, the combination with a keeper, of a tongue adapted for engagement therewith and including normally overlying superimposed offset sections, locking heads on the ends of said sections, and means on the keeper for moving said sections automatically into registry on engagement therewith. 110
7. In a closure fastener a tongue comprising a strip of flexible material doubled upon itself to form overlapped offset sections, the ends of said sections being provided with oppositely directed locking heads, and the lengths of said sections being such that one of the heads is disposed slightly in advance of the other. 115
